MOTOR CONTROL SYSTEM

Thomas Charles Gower, Greenville, S. C.

Application May 19, 1945, Serial No. 594,623

17 Claims. (CL. 172—279)

1

This invention relates to motor control systems, and more particularly but without limitation to a motor control system adapted for use with automatic door operating mechanisms.

In various industrial installations, processing rooms according to current practice are often air-conditioned to maintain a proper atmosphere for the process being carried out. In certain instances, notably the textile industry, air-conditioning is commonly used in this manner, and is a critical factor affecting the ease with which the processing is accomplished.

The problem has arisen in this connection of regulating the use of door openings to such air-conditioned processing rooms so as to prevent the opening of doors leading from unconditioned areas, or from the outdoors, from dissipating the air-conditioning established in the processing room. Door openings to processing rooms are normally used at frequent intervals for delivering materials to be processed and removing processed materials, and as such materials are commonly handled with industrial trucks requiring relatively large door openings, the problem of regulating the use of the door openings has assumed serious proportions.

A variety of arrangements have heretofore been proposed to serve as door operating mechanisms, but most of the previous arrangements have not been sufficiently automatic to solve the present problem, and, on the whole, they have been relatively expensive.

The motor control system of the present invention provides a fully automatic means for controlling a door operating mechanism, and utilizes relatively inexpensive equipment. The control system is arranged so that the door operating mechanism may be set in motion by a single actuation of a pushbutton, photoelectric cell, or other similar control, such as might be easily accomplished by a person passing the location of the pushbutton on an industrial truck. Once in motion, the door is operated by my control system to move to open position, to remain in open position for a predetermined time interval, and then to return to closed position automatically. Further provision is made to allow the door to be reopened by means of the pushbutton control at any time during its travel to closed position, and to cause the door to reopen if it strikes an obstruction at any time during its closing travel.

My motor control system contemplates the control of a single phase electric motor of the type having a starting winding and associated means

2

for disconnecting the starting winding after the motor has started.

An important feature of my invention is the arrangement of an auxiliary, constant speed, high resistance, timing motor in relation to the above mentioned single phase motor as the timing element in my control system.

Another important feature is an arrangement for bridging the disconnecting means associated with the starting winding so that the starting winding may be connected to reverse the single phase motor while it is running.

The foregoing and other features of my invention are illustrated in the accompanying drawing, in which:

Fig. 1 is a circuit diagram illustrating an embodiment of the motor control system of my invention adapted for use in a door operating mechanism;

Fig. 2 is a fragmentary elevation, mainly diagrammatic, illustrating an arrangement of a door operating mechanism incorporating my motor control system;

Fig. 3 is a corresponding elevation, partly cut away, of the operating unit;

Fig. 4 is a corresponding right side elevation;

Fig. 5 is a corresponding rear elevation; and

Fig. 6 is a further diagrammatic view illustrating an arrangement of an overhead door for operation according to my invention.

Referring at first to Fig. 2 of the drawing, an operating unit incorporating my motor control system is indicated generally at 10, arranged for operating a sliding door 11. The illustration in Fig. 2 is mainly diagrammatic, and it will be understood that the door 11 is arranged in relation to a door opening (not shown) and may be moved to allow passage through or to close this door opening as desired. The disposition of the door 11 shown in Fig. 2 is for closed position. The door 11 is mounted on an inclined rail hanger 12 by means of brackets 13 which are attached to the door 11 and fitted with rollers 14 which operate in the inclined rail hanger 12. When

45 moved to open position the door 11 travels up the inclined rail hanger 12 on the rollers 14.

The operating unit 10 comprises an electric motor 15 which is suitably arranged through a belt and pulley connection 16 and other geared connections, to be described more in detail below, to operate a drive sprocket 17. A sprocket chain 18 associated with this drive sprocket 17 is extended across the top of the door 11 to an idler sprocket 19.

55 The door 11 is connected with the sprocket

chain 18 by a bracket 20 which is attached to the door and has a cylindrical portion 20a arranged at its upper end through which the sprocket chain 18 may be passed. A suitable lug member 21 which will not pass through the hollow cylindrical portion 20a of the bracket 20 is arranged toward the lower inclined end of the rail hanger 12. This arrangement allows the door 11 to be opened by hand in case of power failure, or in emergencies, or when otherwise desired.

The sprocket chain 18 extends beyond both the drive sprocket 17 and the idler sprocket 19 in a length sufficient to allow for opening and closing travel of the door 11. The ends of the sprocket chain 18 are secured at fixed mountings 22 and 23. Between these mountings 22 and 23 and the drive sprocket 17 and idler sprocket 19, respectively, the slack of the sprocket chain 18 is disposed in loops 24 and 25. Counterweights 26 and 27 are arranged on rollers 28 operating in these loops. The counterweights 26 and 27 are provided to balance the weight of the door 11, and to keep the sprocket chain 18 taut at all times.

The sprocket chain 18 is actuated for opening and closing the door through the drive sprocket 17 by the geared connections to the motor 15 shown in Figs. 3 and 4. This arrangement comprises a countershaft 29 running from the belt and pulley connection 16 from the motor 15. The countershaft 29 is mounted in suitable bearings 30 in the operating unit housing, and carries a worm 31 and suitable spacing collars 32 all of which are fixed on the countershaft 29 with set screws as shown. The worm 31 is disposed to engage a worm wheel 33 which is fixed on a drive shaft 34 arranged at right angles to countershaft 29 for driving the drive sprocket 17. This drive shaft 34 is also journaled in the operating unit housing and also carries a worm 35 disposed to engage a worm wheel 36 fixed on a switch control shaft 37 which in turn is arranged at right angles to drive shaft 34 and parallel to countershaft 29. The drive shaft 34 and switch control shaft 37 are suitably provided with spacing collars similar to the collars 32 arranged on countershaft 29. The switch control shaft 37 is journaled in the operating unit (as at 38) with an extending switch operating portion 39 to be described more in detail below.

The manner in which my motor control system may be used for operating a door closure arranged in this manner may be described with reference to the circuit diagram shown in Fig. 1.

As mentioned above my motor control system is adapted for controlling a single phase electric motor of the type having a starting winding and associated means for disconnecting the starting winding after the motor has started. A convenient and readily available motor of this type is a capacitor motor such as is commonly used on electrical appliances of various kinds. Capacitor motors are characteristically equipped with a centrifugal switch arranged in the circuit of the starting winding to disconnect the starting winding after the motor has started.

A circuit diagram of an electrical motor 15 of this type is indicated generally in Fig. 1 at 40. The running winding of the motor 15 is represented at 41, the starting winding at 42, and the centrifugal switch arranged in the circuit of the starting winding at 43. In arranging the capacitor motor 15 as at 40 for use with the motor control system of my invention, a reversing switch 44 is also provided in the circuit of the starting winding as indicated in Fig. 1.

Starting with the operating unit 10 at rest and the door 11 in closed position, the capacitor motor 15 is provided with two line switches 45 and 46 in series with the running winding 41. One of these line switches 45 is initially closed and the other one 46 is open. A low voltage control circuit 47 (suitably 18 to 24 volts) containing a push-button control 48 and a relay 49 in series is connected across the line through a transformer 50. The relay 49 is arranged so that when it is not energized a connection is made across the line switch 46 referred to above as initially closed.

The relay 49 is energized by momentarily closing the pushbutton 48. When energized in this manner the relay 49 is shifted to the position indicated by dotted lines in Fig. 1. This causes the above mentioned connection across the line switch 46 to be broken while three other connections are made: one across the line to the capacitor motor 15, which causes it to start rotation in the direction for opening the door 11; another which places a bridging circuit across the centrifugal switch 43 arranged in the circuit of the starting winding 42; and a third in series with contacts 55, 56, to provide a holding circuit for relay 49.

Shortly after the capacitor motor 15 is started, mechanical means correlated with the rotation of the motor 15 (see Figs. 3, 4 and 5) close the initially open line switch 46 so that the motor is then connected and continues to run directly on the line. The mechanical means for closing the line switch 46 comprises an arm 51 mounted on the extending switch operating portion 39 of the switch control shaft 37. The arm 51 turns with rotation of the switch control shaft 37 to contact the switch arm 52 of line switch 46 and shift it to closed position as indicated by the dotted line in Fig. 1.

At about the same time, further mechanical means also associated with the extending switch operating portion 39 of the switch control shaft 37 effects an opening of the above-mentioned bridging circuit across the centrifugal switch 43. This circuit is opened between two contact points 53 and 54 which are arranged in the nature of a push-button switch as indicated in Fig. 1. The contact points 53 and 54, as is best shown in Fig. 4, are carried on a suitably insulated mounting 55 on the operating unit housing, and the lower contact 54 is arranged to spring away when not held in contact with the upper contact 53. A friction collar 56, fitted with a lining of friction material 57 (see Fig. 3), is mounted on the extending switch operating portion 39 of the switch control shaft 37 to dispose an operating arm 58 in relation to the contacts 53 and 54. With the operating unit 10 at rest and the door 11 closed, the operating arm 58 will have assumed a position, as shown in Fig. 4, to close the contacts 54 and 53. Rotation of the switch control shaft 37 in the direction corresponding to opening of the door 11, however, will cause the operating arm 58 to shift to the position indicated by dotted lines in Fig. 4 so that the lower contact 53 will spring away from the upper contact 54. This shift is caused by the fact that the friction collar 56 is fitted on the extending portion 39 of shaft 37 tightly enough to rotate with it when not opposed. The operating arm 58 accordingly turns with rotation of shaft 37 until it is restrained by a stop 59 extending from the mounting 55. The friction collar 56 will then slip on shaft 37 during continued rotation in the same direction. As ex-

plained more in detail below, operating arm 58 is shifted back to initial position by rotation of the shaft 37 in the direction corresponding to closing of the door 11. A stop 60 for the operating arm 58 in this position is formed in the lower contact 54.

Opening of the contacts 53 and 54 as described above conditions the bridging circuit across the centrifugal switch 43 so that the starting winding 42 may be cut out as soon as the motor 15 attains speed during operation for opening the door 11.

The motor 15 continues to operate under these conditions until the door 11 has been moved to open position. When the door 11 has been opened, the motor 15 is stopped by a second arm 61 mounted on the extending portion 39 of the switch control shaft 37 which engages the switch arm 62 of the initially closed line switch 45 and shifts it to open position. At the same time, arm 61 shifts the switch arm 63 of reversing switch 44 to reverse the connections of the starting winding 42 to condition the motor 15 for reverse operation to close the door 11.

An auxiliary, constant speed, high resistance, timing motor 64 is connected in parallel with the initially closed line switch 45, so that when the line switch 45 is opened to stop the capacitor motor 15 the timing motor 64 is connected in series with the running winding 41 of the motor 15. While the timing motor 64 will operate under these circumstances, its high resistance prevents operation of the capacitor motor 15.

The timing motor 64, which may be of the well known shaded-coil type, is used to time the period during which the door 11 remains in open position. The timing is accomplished through actuation of contacts 65 and 66 which, like contacts 53 and 54, are also arranged in the nature of a push-button switch as indicated in Fig. 1. The contacts 65 and 66 are disposed from a suitable mounting as at 67 in relation to a notched timing element 68 carried on the shaft of the timing motor 64 (see Figs. 4 and 5). The timing element 68 is an electrical conductor, and has a substantially cup-like cylindrical shape in which notches 68a are formed at the open end. As is best shown in Fig. 4, the contact 65 rides a solid portion of the element 68 as it rotates during operation of the timing motor 64, while the contact 66 is positioned in relation to the notched portion. As a result, the contact 66 will periodically slip across one of the notches 68a in the timing element 68 and momentarily break the connection between contacts 65 and 66 through the element 68. By employing a timing element 68 having notches 68a of suitable size in relation to the speed of the timing motor 64 the periodic breaking of the connection between contacts 65 and 66 can be arranged to occur at desired intervals corresponding to the length of time it is intended to have the door 11 remain in open position.

The contacts 65 and 66 are arranged in the control circuit 41 so that when the connection between these contacts is momentarily broken, as contact 66 slips across a notch 68a in the timing element 68, the relay 49 is de-energized. The relay 49 accordingly assumes its original position to make a connection across the line switch 45 which was opened to stop the capacitor motor 15 when the door 11 reached open position. As line switch 45 is bridged in this manner, and line switch 46 was closed when motor 15 was first started to open the door 11, motor 15 is again connected on the line and will resume operation;

and as reversing switch 44 was shifted when line switch 45 was opened, motor 15 will resume operation in the direction corresponding to closing movement of the door 11.

When the line switch 45 is bridged out at the time that relay 49 is de-energized, the timing motor 64 is also bridged out and consequently will not operate. As the timing motor 64 is stopped in this manner when the contact 66 slips across a notch 68a in the timing element 68, the motor 64 will stop in each instance with the contact 66 resting on the lower edge of a notch 68a in the timing element 68. By arranging the notches 68a regularly in the timing element 68, a uniform timing of the period for holding the door 11 in open position can thus be obtained.

Shortly after operation of the capacitor motor 15 resumes in the direction necessary to close the door 11, arm 61 on the extending portion 39 of

switch control shaft 37 will again engage switch arms 62 and 63, respectively, to close line switch 45 and again shift the reversing switch 44 to reverse the connections on the starting winding 42. This action of the arm 61 is timed to occur after the

capacitor motor 15 has attained speed and the starting winding 42 has consequently been cut out by the centrifugal switch 43. At about the same time, the operating arm 58 on the friction collar 56 shifts back to its original position to

close contacts 53 and 54 in the bridging circuit across the centrifugal switch 43. As the relay 49 has been de-energized, however, this bridging circuit is open at the relay.

Under these conditions, the capacitor motor 15 may continue operation until the door 11 has been closed, the capacitor motor 15 being stopped by the action of arm 51 which will engage switch arm 52 at this time to shift line switch 46 to open position and thus open the line on capacitor motor 15.

As previously mentioned, further provision is made to allow the door 11 to be reopened by means of the push-button control 48 at any time during its travel to closed position, and to cause it to re-open if an obstruction is met at any time during closing travel.

Reopening of the door 11 with the push-button control 48 is effected through the bridging circuit from the relay 49 across the centrifugal switch 43.

If the push-button 48 is closed at any time during closing travel of the door 11, the relay 49 will be energized to close this bridging circuit across the centrifugal switch 43 and thus bring the starting winding 42 into play. As the reversing switch

44 is in position at this time to connect the starting winding 42 for rotation of the motor 15 in the direction for opening the door 11, the starting winding 42 will oppose the running winding 41 and reverse the direction of rotation of the motor

15 to reopen the door 11. A resistance element 69 is placed in the starting winding circuit to act as a buffer and protect the starting winding 42 during operation in this manner.

When the capacitor motor 15 is reversed as described above to reopen the door 11, the operating arm 58 on the friction collar 56 will shift as opening movement starts to open the contacts 53 and 54 so that the starting winding 43 may be cut out

by the centrifugal switch 43 as soon as motor 15 attains speed in the changed direction. The motor 15 will be controlled to stop when the door 11 reaches open position, the interval in open position will be timed and the motor 15 will be operated to close the door 11, as noted above in de-

scribing the operation of the control system under normal conditions.

The door 11 is caused to reopen if it meets an obstruction by a safety switch 10 mounted on springs on the leading edge of the door 11 as illustrated in Fig. 2. The safety switch 10 is arranged in the manner of a push-button to close auxiliary contacts 10a in the control circuit 47 as shown in Fig. 1. Closing of these auxiliary contacts 10a effects reopening of the door 11 in the same way that actuation of the push-button control 48 accomplishes this result as described above. The safety switch 10 may be of the contact pressure type, or of any other conventional design adapted for this purpose.

A further safety provision is included in my motor control system to guard against damage to the operating unit 10 in the event of a power failure. If a power failure interrupted operation during opening movement of the door 11, the relay 49 would of course be de-energized; but, as both line switches 45 and 46 would be closed at this time, operation to open the door 11 would be resumed when the power failure was remedied. With relay 49 de-energized, however, the opening of line switch 45 would not be effective to stop motor 15 when door 11 reached open position because switch 45 would be bridged out at de-energized relay 49. As a result, motor 15 would continue to operate until the transmission became locked. To avoid this possibility in the event of a power failure, an auxiliary switch 45a (see Fig. 1) is arranged to control a bridging circuit connected directly across the centrifugal switch 43. The switch 45a is arranged so that it is closed and opened simultaneously with opening and closing, respectively, of line switch 45. Consequently, if relay 49 is deenergized for any reason so as to allow motor 15 to continue operation in opening direction, switch 45a will bring the starting winding 42 into play as line switch 45 is opened; and as reversing switch 44 will be shifted to reverse the connections of starting winding 42 when line switch 45 is opened, the capacitor motor 15 will be reversed so that door 11 will return immediately to closed position, thus avoiding the possibility of damage to the operating unit 10. Any danger resulting from sudden resumption of movement of the door 11 in this manner is obviated by the provision of the above described safety switch 10.

To arrange the door 11 for operation from either side, a second push-button control 71 may be placed in parallel with the push-button 48 as shown in Fig. 1. If desired, photoelectric cells (not shown) or other means for automatically actuating the relay 49 may be substituted for the push-buttons 48 and 71.

An adaption of my motor control system for operating an overhead door is illustrated diagrammatically in Fig. 6. The overhead door is represented at 12 as the well known type composed of hinged panels and adapted to be raised overhead to open position on rollers operating in curved guideways (not shown). Tension springs 13 are commonly used on a door installation of this type to carry the major portion of the weight of the door 12 when it is moved to open position but not to resist closing movement of the door unduly. In adapting such a door for operation according to my invention, the springs 13 are tightened so that they will raise the door 12 to open position unaided if not resisted. The pull of the springs 13 is exerted on the door 12 through lines 14 which have a fixed mounting

at 15 and run over pulleys 16 which are movable with the springs 13 and fixed pulleys 11 to a point of attachment 18 at the bottom of the door 12.

The door 12 is held in closed position against the pull of springs 13 through a line 19 running from a fixed mounting 20 over rollers 21 mounted at the bottom of the door. It will be seen that the door 12 may be readily opened in emergencies with this arrangement by cutting the line 19.

10 Beyond the rollers 21 the line 19 is led around a fixed pulley 22 and over a movable pulley 23 to a fixed mounting 24. The movable pulley 23 is carried at the end of a line 25, suitably a sprocket chain, engaged by the point of drive 26 of the door operating unit represented in this instance at 27. A counterweight 28 is arranged on the other end of the line 25 to balance the pull of springs 13 approximately.

An operating unit 27 which is in all respects 20 identical with the embodiment described above for operating a sliding door 11 may be used to operate the overhead door 12. As the operating unit 27 is started for opening movement of the door 12, the effect is to pay out the line 25 so 25 that the door may be raised by the springs 13. The counterweight 28 insures smooth operation as this opening movement occurs. After the door 12 has been timed in open position, the operating unit 27 is caused to start in closing direction and the door 12 is closed against the pull of springs 13 with the aid of counterweights 28.

The overhead door 12 may be reopened automatically, or as desired during closing movement, in the same manner as was described in 35 detail above in connection with the operation of the sliding door 11.

While my motor control system has been described above in connection with its embodiment for use in a door operating mechanism, it will be 40 understood that my invention is not limited in this respect and that the motor control system described is of general application as defined in the appended claims.

I claim:

45 1. A motor control system comprising a single phase electric motor of the type including a starting winding and associated means for automatically disconnecting the starting winding after the motor has started, means for starting said 50 motor for rotation in a given direction, means for automatically stopping said motor when a predetermined degree of rotation in said given direction has been obtained, means for automatically restarting said motor after a predetermined 55 time interval for rotation in reverse direction with respect to said first mentioned direction of rotation, means for automatically stopping said motor when it has returned to initial position by virtue of said reverse rotation, and controllable 60 means for changing the direction of rotation of said motor to said first mentioned direction of rotation at any time during said reverse rotation.

65 2. A motor control system comprising a single phase electric motor of the type including a starting winding and associated means for automatically disconnecting the starting winding after the motor has started, means for starting said motor for rotation in a given direction, means for automatically stopping said motor when a predetermined 70 degree of rotation in said given direction has been obtained, an auxiliary, constant speed, high resistance, electric timing motor, means for automatically connecting said timing motor in series with said single phase motor simultaneously with the stopping of rotation of said single

phase motor in said given direction, means associated with said timing motor for automatically restarting said single phase motor after a predetermined time interval, means for automatically conditioning said single phase motor for rotation upon restarting in reverse direction with respect to said first mentioned direction of rotation, and means for automatically stopping said single phase motor when it has returned to initial position by virtue of said reverse rotation.

3. A motor control system comprising a single phase electric motor of the type including a starting winding and associated means for automatically disconnecting the starting winding after the motor has started, means for starting said motor for rotation in a given direction, means for automatically stopping said motor when a predetermined degree of rotation in said given direction has been obtained, an auxiliary, constant speed, high resistance, electric timing motor, means for automatically connecting said timing motor in series with said single phase motor simultaneously with the stopping of rotation of said single phase motor in said given direction, means associated with said timing motor for automatically restarting said single phase motor after a predetermined time interval, means for automatically conditioning said single phase motor for rotation upon restarting in reverse direction with respect to said first mentioned direction of rotation, means for automatically stopping said single phase motor when it has returned to initial position by virtue of said reverse rotation, and controllable means for changing the direction of rotation of said motor to said first mentioned direction of rotation at any time during said reverse rotation.

4. In a motor control system for a single phase electric motor of the type including a starting winding and associated means for automatically disconnecting the starting winding after the motor has started, a means for automatically interrupting the operation of said single phase motor for a predetermined time interval comprising means for automatically stopping said single phase motor, an auxiliary, constant speed, high resistance, electric timing motor, means for automatically connecting said timing motor in series with said single phase motor simultaneously with the stopping of said single phase motor, and means associated with said timing motor for automatically restarting said single phase motor after said predetermined time interval.

5. In a motor control system for a single phase electric motor of the type including a starting winding and associated means for automatically disconnecting the starting winding after the motor has started, a means for automatically interrupting the operation of said single phase motor for a predetermined time interval comprising a line switch in the operating circuit to said single phase motor, means for automatically opening said line switch, an auxiliary, constant speed, high resistance, electric timing motor connected in parallel with said line switch, and means associated with said timing motor for automatically closing the operating circuit to said single phase motor after a predetermined time interval.

6. In a motor control system for a single phase electric motor of the type including a starting winding and associated means for automatically disconnecting the starting winding after the motor has started, a means for automatically interrupting operation of said single phase motor for a predetermined time interval comprising

means for automatically stopping said single phase motor, an auxiliary, constant speed, high resistance, electric timing motor, means for automatically connecting said timing motor in series with said single phase motor simultaneously with the stopping of said single phase motor, and means associated with said timing motor for automatically restarting said single phase motor after said predetermined time interval, said associated

10 means including an element mounted for rotation on the shaft of said timing motor and adapted to close the operating circuit to said single phase motor after said predetermined time interval.

15 7. Means for automatically interrupting the operation of a capacitor motor for a predetermined time interval comprising a line switch in the operating circuit to said capacitor motor, means for automatically opening said line switch, an auxiliary, constant speed, high resistance, electric timing motor connected in parallel with said line switch, and a bridging circuit and means associated with said timing motor for connecting said bridging circuit across said open line switch after said predetermined time interval.

20 8. In a control system for a capacitor motor, an operating line circuit to said capacitor motor, a control circuit in parallel with said operating circuit, a relay in said control circuit, means for closing said control circuit to energize said relay, means closing the operating circuit to start said capacitor motor when said relay is energized, a line switch in said operating circuit, means for automatically opening said line switch

25 30 35 40 means for automatically stopping said capacitor motor, an auxiliary, constant speed, high resistance, electric timing motor connected in parallel with said line switch, means associated with said timing motor to de-energize said relay after a predetermined time interval, and means for closing the operating circuit to restart said capacitor motor when said relay is de-energized.

45 9. A motor control system comprising a single phase electric motor of the type including a starting winding and associated means for automatically disconnecting the starting winding after the motor has started, means for starting said motor for rotation in a given direction, means for automatically stopping said motor

50 55 50 when a predetermined degree of rotation in said given direction has been obtained, means for automatically restarting said motor after a predetermined time interval for rotation in reverse direction with respect to said first mentioned

60 65 60 direction of rotation, means for automatically stopping said motor when it has returned to initial position by virtue of said reverse rotation, and controllable means for changing the direction of rotation of said motor to said first mentioned direction of rotation at any time during said reverse rotation, said controllable means comprising a bridging circuit across the means for automatically disconnecting the starting winding after the motor has started and means for closing said bridging circuit to connect said starting winding.

70 75 70 75 10. In a motor control system for a capacitor motor having a centrifugal switch for disconnecting the starting winding of said capacitor motor after said motor has started, an operating circuit for said motor, a control circuit in parallel with said operating circuit, a relay in said control circuit, means for closing said control circuit to energize said relay, a bridging circuit across said centrifugal switch, said bridging cir-

11

cuit being connected for closing at said relay when said relay is energized, means for reversing said motor, means for maintaining said bridging circuit open while said motor is operating in one direction of rotation but conditioning said bridging circuit to be closed by energizing said relay during reverse rotation of said motor with respect to said first mentioned direction of rotation, whereby the starting winding may be connected to change the direction of rotation of said motor to said first mentioned direction of rotation at any time during the reverse operation of said motor.

11. In a motor control system for a single phase electric motor of the type including a starting winding and associated means for disconnecting the starting winding after the motor has started, means for reversing said motor, a bridging circuit across the means for disconnecting the starting winding, means maintaining said bridging circuit open while said motor is operating in one direction of rotation but conditioning said bridging circuit for closing during reverse operation of said motor with respect to said first mentioned direction of rotation, whereby the starting winding may be connected to change the direction of rotation of said motor to said first mentioned direction of rotation at any time during the reverse operation of said motor, said last mentioned means comprising a collar member mounted in frictional engagement with the shaft of said single phase motor for rotation with said shaft except when opposed, contacts arranged in said bridging circuit in normally open position, means associated with said collar member for closing said contacts, said associated means being moved by said collar member upon rotation of said motor in said first mentioned direction to a position allowing said contacts to assume an open position and being moved to a position closing said contacts upon reverse rotation of said motor, and means for opposing rotation of said collar member to limit movement of said associated means between positions corresponding to open and closed positions of said contacts.

12. A door closure means comprising a door movable to open and closed positions and a single phase electric motor, of the type including a starting winding and associated means for disconnecting the starting winding after the motor has started, connected for moving said door between open and closed position, means for starting said motor to move said door to open position, means for automatically stopping said motor when said door has been moved to open position, and means for automatically restarting said motor to move said door to closed position after a predetermined time interval.

13. A door closure means comprising a door movable to open and closed positions and a single phase electric motor, of the type including a starting winding and associated means for disconnecting the starting winding after the motor has started, connected for moving said door between open and closed position, means for starting said motor to move said door to open position, means for automatically stopping said motor when said door has been moved to open position, means for automatically restarting said motor to move said door to closed position after a predetermined time interval, and means for reversing said motor to reopen said door at any time during operation of said motor to close said door.

14. A door operating mechanism for control-

12

ling the movement of a door normally maintained in closed position comprising a single phase electric motor, of the type including a starting winding and associated means for disconnecting the starting winding after the motor has started, connected for moving said door between open and closed position, means for operating said motor in one direction of rotation to move said door to open position, means for maintaining said door in open position for a predetermined time interval, means for operating said motor in reverse direction with respect to said first mentioned direction of rotation to move said door to closed position after said predetermined time interval, and means for changing the direction of rotation of said motor to said first mentioned direction of rotation to return said door to open position at any time during operation of said motor to move said door to closed position.

15. A door operating mechanism for controlling the movement of a door normally maintained in closed position comprising a capacitor motor having a centrifugal switch for disconnecting the starting winding of said capacitor motor after said motor has started, an operating circuit for said motor, a control circuit in parallel with said operating circuit, a relay in said control circuit, means for closing said control circuit to energize said relay, means closing said operating circuit when said relay is energized, whereby said capacitor motor is operated to move said door to open position, a line switch in said operating circuit, means for automatically opening said line switch to stop said capacitor motor when said door reaches open position, means for automatically reversing the connections of the starting winding of said capacitor motor when said door reaches open position, an auxiliary, constant speed, high resistance, electric timing motor connected in parallel with said line switch, whereby said timing motor is connected in series with said capacitor motor and operates when said line switch is open, means associated with said timing motor to de-energize said relay after a predetermined time interval, means for bridging said line switch to close said operating circuit when said relay is de-energized, whereby said capacitor motor is operated in reverse direction to close said door after said predetermined time interval, means for automatically reversing the connections of said starting winding to condition said capacitor motor for operation to open said door after said reverse operation has started, and means to connect said starting winding to cause said capacitor motor to reopen said door at any time during reverse operation of said motor to close said door.

16. In a control system for a capacitor motor of the type having a starting winding and a centrifugal switch for disconnecting the starting winding after the motor has started, an operating line circuit to said capacitor motor, a control circuit in parallel with said operating circuit, a relay in said control circuit, means for closing said control circuit to energize said relay, means closing the operating circuit to start said capacitor motor when said relay is energized, a line switch in said operating circuit, means for automatically opening said line switch to stop said capacitor motor and associated means for concurrently conditioning said capacitor motor for reverse operation, an auxiliary, constant speed, high resistance, timing motor connected in parallel with said line switch, means associated with said timing motor to de-energize said relay after a predetermined time interval, a bridging circuit across

said open line switch and means closing said bridging circuit when said relay is deenergized, and a second bridging circuit across said centrifugal switch and means for closing said second bridging circuit simultaneously with opening of said line switch, whereby operation of said capacitor motor is automatically reversed when said line switch is opened if said relay has previously been accidentally de-energized.

17. In a motor control system for a single phase electric motor of the type having a starting winding and associated means for disconnecting the starting winding after the motor has started, an operating line circuit to said single phase motor, a control circuit in parallel with said operating circuit, a relay in said control circuit, means for closing said control circuit to energize said relay, means closing the operating circuit to start said single phase motor when said relay is energized, a line switch in said operating circuit, means for automatically opening said line switch to stop said single phase motor and associated means for concurrently conditioning said single phase motor for reverse operation, means for de-energizing said relay after a predetermined time

15 5 interval, a bridging circuit across said open line switch and means closing said bridging circuit to restart said single phase motor in reverse direction when said relay is de-energized, and a second bridging circuit across said associated means for disconnecting the starting winding and means for closing said second bridging circuit simultaneously with opening of said line switch, whereby operation of said single phase motor is automatically reversed when said line switch is opened if said relay has previously been accidentally de-energized.
